WITNESS:

UNITED STATES PATENT OFFICE

CASIMIR MAGDITS, OF MERRICK, NEW YORK

BOAT

Application filed September 25, 1929. Serial No. 395,140.

This invention relates to improvements in boats and has especial relation to hulls, an object being to provide a boat hull which will offer a minimum amount of resistance to the action of the water, so that the hull will remain practically upon an even keel at all times, while the character of the hull will increase the speed of the boat for a given amount of power.

With the above and other objects in view, the invention further includes the following novel features and details of construction, to be hereinafter more fully described, illustrated in the accompanying drawings and pointed out in the appended claims.

In the drawings:—

Figure 1 is an elevation partly broken away showing the boat hull constructed in accordance with the invention.

Figure 2 is a top plan view.

Figure 3 is an end view.

Figures 4, 5 and 6 are sections taken respectively on the lines 4—4, 5—5 and 6—6 of Figure 2.

Referring to the drawings in detail where in like characters of reference denote corresponding parts, the boat, as shown at 10 in Figure 2 of the drawings, is pointed at both ends so as to decrease water resistance at the forward end of the boat and reduce drag at the rear end.

The hull is provided with a keel 11 which is substantially V shaped in cross section and which extends throughout the length of the hull. The sides of the keel 11 are inwardly curved as indicated at 12 and merge into outwardly curved bulbous portions 13. By reference to Figures 3, 5 and 6 of the drawings it will be seen that the bottom of the hull upon opposite sides of its transverse center provides a compound curve of sections which meet at the point of the keel and which extend outwardly and downwardly around the bulbous portions 13. The bottom of the keel is spaced slightly below the lowest point of the bottom of the hull and the bottom provides longitudinally disposed depressions or channels for the passage of water beneath the hull while the character of the bulbous portions resists side motion of the

hull. The shape of the bottom of the hull is also such as to eliminate pounding in heavy seas.

These bulbous portions 13 also extend throughout the length of the hull and the opposite sides of said hull curve inwardly from the bulbous portions as shown at 14. Outwardly curved overhanging portions 15 extend from these inwardly curved portions 14 and the latter together with the outwardly curved overhanging portions 14 act to deflect heavy seas upwardly and outwardly so that the force of the seas will be broken due to the glancing effect produced by the shape of the hull. The inwardly and outwardly curved portions 14 and 15 also extend throughout the length of the hull so that the pointed ends 10 also provide similarly shaped portions as shown in Figure 1. The shape of the pointed ends of the hull further acts to reduce water resistance during the forward movement of the hull and to reduce drag at the stern.

From the foregoing description and accompanying drawings it will be seen that the invention provides a boat hull used for boats of various sizes and character from the smallest boat to the largest seagoing vessel. The character of the hull is such as to decrease water resistance when the boat is under way and to cause heavy seas to glance off the hull so that the latter will not receive the full impact of these seas. This will act to stabilize the hull in heavy seas so that the boat will remain upon an even keel in severest weather and the comfort and safety of the passengers will thus be assured.

The invention is susceptible of various changes in its form, proportions and minor details of construction and the right is herein reserved to make such changes as properly fall within the scope of the appended claims.

Having described the invention what is claimed is:—

1. In a boat, a hull having a substantially V-shaped keel whose side walls merge into the bottom of the hull on opposite sides of the keel, an outwardly and downwardly disposed bulbous portion extending from each side of the keel, upwardly and inwardly

curved portions extending from the bulbous portions, and defining together with the outwardly and downwardly bulbous portion, an outwardly and downwardly curved portion, and outwardly curved overhanging portions extending from the upwardly and inwardly curved portions.

2. In a boat, a hull pointed at both ends, a substantially V-shaped keel extending throughout the length of the hull, an outwardly and downwardly disposed bulbous portion extending from each side of the keel throughout the length of the hull, upwardly and inwardly curved portions extending from the bulbous portions also throughout the length of the hull, and outwardly curved overhanging portions extending from the upwardly and inwardly curved portions, all of said curved portions meeting at the pointed ends of the hull and defining a hull whose outer surface is of substantially the same contour throughout its length.

In testimony whereof I affix my signature.
